Patented May 30, 1905.

UNITED STATES PATENT OFFICE.

ERNST DOSSMANN, OF PRILLWITZ, GERMANY.

POTATO-DIGGER.

SPECIFICATION forming part of Letters Patent No. 791,140, dated May 30, 1905.

Application filed February 8, 1904. Serial No. 192,723.

To all whom it may concern:

Be it known that I, ERNST DOSSMANN, farmer, a subject of the Emperor of Germany, residing at Prillwitz, near Eichberg, county of Fi- 5 lehne, Germany, have invented certain new and useful Improvements in Plows of Potato-Diggers; and I do hereby declare the following to be a full, clear, and exact description of my invention.

10 In the accompanying drawings, Figure 1 is a front elevation of my plows, which are constructed in accordance with my invention. Fig. 2 is a horizontal section on the line $\alpha\alpha$, Fig. 1.

15 My plows or shovels a , bent in form of a scoop extending downwardly and with their points against each other, are suitably attached near the back end each to a longitudinal side of a potato-digger frame b . These plows or 20 shovels a are provided above with a shaft c of suitable form, which is able to slide in sockets d , fastened to the frame b , thereby making

the plows adjustable in height. The shafts c are fixed in the sockets d by screws h .

The plows are adapted to enter the row of 25 potatoes and discharge the earth over the said plows. The cutting edges g are curved from the front edge to the back edge, forming thereby points e . These points are bent somewhat upwardly and the back edges i somewhat outwardly. 30

Having thus described my invention, what I claim, and desire to secure by Letters Patent, is—

35 In a potato-digger the combination of two opposite plows each bent in form of a scoop, having curved cutting edges with points being bent somewhat upward and the back edges of the plows being bent somewhat outward, as and for the purpose specified.

ERNST DOSSMANN.
